UNITED STATES PATENT OFFICE.

GEORGE C. DAVIS, OF CHICAGO, ILLINOIS, ASSIGNOR TO G. M. DAVIS REGULATOR COMPANY, OF CHICAGO, ILLINOIS, A CORPORATION OF ILLINOIS.

NONRETURN VALVE.

Application filed March 14, 1927. Serial No. 175,290.

My invention relates to improvements in nonreturn valves where it is desirable to have an exceedingly sensitive valve which will respond to very slight changes in pressure and where the valve will be absolutely tight without the introduction of any special or separate packing means and wherein the valve parts will offer a minimum resistance to flow in the open direction and wherein the floating valve members may be adjusted, replaced and manipulated with a minimum of difficulty and complication. Other objects will appear from time to time in the course of the specification and claims.

My invention is illustrated more or less diagrammatically in the accompanying drawings, wherein—

Figure 1 is a side elevation of the valve;

Figure 2 is a section along the line 2—2 of Figure 1;

Figure 3 is a section along the line 3—3 of Figure 1.

Like parts are indicated by like characters throughout the specification and drawings.

A is the valve casing; A¹ the intake and A² the discharge pipe so that gas or air flows through the valve in the direction shown by the arrow. The underside of the housing is bounded by a curved wall as at A³; the upper side which is open terminates in a flange A⁴ extending clear across the area of the valve. A⁵ is an extension housing adapted to be bolted to the flange A⁴ and closed by the cap A⁶.

The inside of the housing is flanged as at B. Resting on this flange and held seated thereon by means of the set screws B¹ B¹ are a plurality of grid member B² B² extending across the effective opening of the valve.

Spaced beyond the down-stream side of these grid members on the down-stream side thereof is a bridge B³ held in place by the studs B⁴. Obviously the grid might be made integral with the valve housing and the extension housing might be integral with the balance of the valve housing though it is more convenient to make them as indicated. Under some conditions the body of the valve housing itself might be used as a substitute for the bridge.

C C are valve plates or shoes of such width as to bridge the gap between adjacent grid members, there being one separate shoe to close the entire space between each adjacent

pair of grid members. The grid members are provided with bearing ribs C¹ on their down-stream faces projecting above the body of the grid adapted to be engaged by the shoe. These members are provided so that each shoe may be ground into place on its part of the grid, thereby making a tight closure when the shoe is seated. Projecting outwardly from the down-stream side of each shoe are two or more lugs C² C³. These lugs make a close working fit on a flexible shoe supporting spring bar C⁴ which is anchored by the pin C⁵ in one of the lugs only to permit differential expansion and contraction of the bar and the shoe while holding the shoe firmly in place on the bar against longitudinal or rotary movement with respect to the bar. Each spring bar extends upwardly and is socketed in a boss C⁶ on the underside of the cover A⁸ being held in position therein by a pin C⁷. It will be noted that the axis of the socket in the boss is slightly inclined and this axis if projected extends slightly upstream from the position occupied by the bar when in place with the shoe. Thus there is a slight initial tension on each spring bar tending to initially seat each shoe in place.

The bridge B³ limits the forward movement of the valve shoes in the direction of flow of the fluid so as to maintain them in proper working relation with the grid. If the direction of flow is reversed, these shoes are thrown back against the grid by the elasticity of the spring bar and by the pressure of the flowing fluid and close the valve. The valve plates are removable as a unit with the cap A⁶, and the grid members tied together as they are by the peripheral ring B⁵ are also removable as a unit from the housing by release of the set screws B¹ so that both the grid and the plate may be easily removed for repair, renewal or change. The long housing through which the spring rods or bars extend upwardly away from the grid permits these bars to be long enough so that flexure or bending is on such a long arc and so slight in degree that crystallization and breakage is reduced to a minimum. The socketing of each spring bar separately in the housing and the bending of each bar together with its socketing in the back of the shoe and the pinning of the bar there enables each bar to definitely and accurately position each shoe and bring it always back

into working relation with the seat on the grid, thus rotation or displacement of the valve shoe is reduced to a minimum and the shoe is always returned to its normal seating position without the use of any guiding or positioning means other than the bridge or other stop which prevents the shoes being driven too far away from their seats.

It will be evident that while I have shown 10 in my drawings an operative device, still many changes might be made in the size, shape, arrangement and disposition of parts without departing materially from the spirit of my invention and I wish, therefore, that 15 my showing be taken as in a sense diagrammatic.

I claim:

1. A non-return valve comprising an apertured valve seat, a shoe adapted to rest upon 20 the seat and close the aperture and an elongated

flexible supporting member extending laterally from the shoe and rigidly anchored at a point removed therefrom, a plurality of lugs projecting rearwardly from the shoe, one of them anchored, the others slidable on 25 the supporting member.

2. A non-return valve comprising an apertured valve seat, a shoe adapted to rest upon the seat and close the aperture and an elongated flexible supporting member extending 30 laterally from the shoe and rigidly anchored at a point removed therefrom, the anchorage for the flexible member comprising a socket in which the end of the member is received and holding means passing through the walls 35 of the socket and the flexible member.

Signed at Chicago, county of Cook and State of Illinois, this 8th day of March, 1927.

GEORGE C. DAVIS.
